UNITED STATES PATENT OFFICE.

FRÉDÉRIC A. S. DIT LALLEMAND AND ARTHUR GRAVEL, OF MONTREAL,
QUEBEC, CANADA.

WASHING-MACHINE.

SPECIFICATION forming part of Letters Patent No. 425,889, dated April 15, 1890.

Application filed December 20, 1888. Serial No. 294,239. (Model.)

To all whom it may concern:

Be it known that we, FRÉDÉRIC ALFRED SURHURIER DIT LALLEMAND and ARTHUR GRAVEL, citizens of the Dominion of Canada, 5 residing at the city and district of Montreal and Province of Quebec, have invented certain new and useful Improvements in Washing-Machines; and we do hereby declare the following to be a full, clear, and exact description of the invention, such as will enable others skilled in the art to which it appertains to make and use the same.

This invention relates to washing-machines; and it consists in the novel construction and combination of the parts hereinafter 15 fully described and claimed.

In the drawings, Figure 1 is a plan view of the machine from above. Fig. 2 is a rear end view. Fig. 3 is a longitudinal vertical section, taken on line xx in Fig. 1. Fig. 4 is a side view of the machine, showing the upper half raised up.

Our invention is composed of the portion A, cut away at B to facilitate the handling, 25 and having its upper surface at C corrugated, as an ordinary wash-board, or provided with small depressions, as shown in Figs. 1 and 3, or any suitable device. It is also provided with the two legs D D, which serve the same 30 purpose as the legs of an ordinary wash-board, and two upright pieces E E, on which is pivoted the two side pieces F F at G G, so that they can revolve around these points for a certain portion of a circumference, the object of which shall be explained hereinafter.

The two side pieces F F are joined together by means of the cross-pieces H and I and have the form shown in the drawings. The piece I is provided with the slot J, through which 40 passes the toothed sector K, provided with the lever L and held in position by means of the shaft M, resting on the standards N, firmly secured on the piece I. This sector K couples on the geared wheel O, attached to the piece I at P, which communicates an alternating 45 motion to the board Q through the medium of the connecting-rod R. This board Q is corrugated like an ordinary wash-board, or otherwise suitably arranged. To press the board 50 Q down firmly against the piece A, we make use of the springs S S, attached at one ex-

tremity to the piece I and resting at the other on the rollers T, secured to the board Q, which slides in the guides V.

The pieces F F are held down on the piece A by means of the hooks W. To introduce a piece of material to be washed between the pieces Q and A, all that is necessary to do is to bring the lever L down until it strikes on the top of the piece a, which is provided with the catch b at its lower extremity, thus pushing it downward in such a way that the moment the lever L begins its upward motion the piece d passes onto the catch b; but the spring f immediately pulls up the piece d, 65 and consequently the board Q, to which it is attached; but during this time, the lever L continuing its upward motion, the board Q has a backward movement—that is, from the gear-wheel O—so that the piece d slips onto 70 the support g until it reaches its extremity h, where it slips off, and consequently the board Q falls down onto the piece A. However, before this takes place—that is, while the board Q is suspended on the support g—the lever L 75 being stopped, the material to be washed is introduced on the piece A, where the board Q, on falling and beginning its forward movement, pulls it along with it and gives it a good rubbing against the piece A in its forward 80 and backward movement. When it is wanted to advance the clothes placed between the boards Q and A, all that is necessary to do is to repeat the operations necessary to raise the board Q and let it drop at the lower end of 85 its course, just described, this bringing the material along with it.

If necessary to raise the whole apparatus off the piece A, all that is necessary to do is to uncouple the hooks W and raise pieces F 90 up with accompanying mechanism, the whole revolving on the pivots G, this also allowing the introduction of clothes.

The piece m serves to arrest the downward motion of the lever L.

Having described our invention, what we claim, and desire to secure by Letters Patent, is—

1. In a washing-machine, the lever L, toothed sector K, geared wheel O, connecting-rod R, 100 board Q, springs S, rollers T, piece a, spring f, catch b, piece d, support g, pieces F, H, and

I, also standards N, all arranged substantially as described, and for the purposes set forth.

2. In a washing-machine, the combination, with the lower wash-board provided with uprights E, of a frame pivoted to said uprights, the spring-actuated catch b and the support g, both attached to said frame, the upper wash-board bearing upon the lower wash-board, the piece d, secured to said upper wash-board, and to a lever for imparting reciprocating motion to

the upper wash-board and causing said catch to engage with piece d at intervals, substantially as and for the purpose set forth.

In testimony whereof we have affixed our signatures in presence of two witnesses.

FRÉD. A. S. DIT LALLEMAND.
ARTHUR GRAVEL.
